UNITED STATES PATENT OFFICE

DAVID LAURENTIUS LIENZÉN, OF STOCKHOLM, SWEDEN, ASSIGNOR TO TELEFON-
AKTIEBOLAGET L. M. ERICSSON, OF STOCKHOLM, SWEDEN, A COMPANY OF SWEDEN

GROUP SELECTOR

Application filed December 28, 1927, Serial No. 243,127, and in Sweden January 5, 1927.

For the purpose of distributing uniformly the telephone traffic on the different junction lines of automatic telephone exchanges it has already been proposed to use pre-selectors or 5 searchers of the kind which have no definite normal position and which, therefore, are started each time from the position into which they have been previously set. Heretofore it has been impossible to provide for a similar 10 mode of operation of group selectors as generally such selectors must be set from a fixed initial position. To obtain a uniform distribution of the traffic over the junction lines leading from such selectors it was therefore 15 necessary to make use of a special wiring of the contact fields of the selectors, so that the selecting of a disengaged junction line of a group of lines will take place in a different order of sequence in the different group 20 selectors having access to the same line group. In some systems, however, such wiring of the contact fields can not be used with advantage. This is for instance the case in systems 25 where the contact field of the selectors consists of bare wires which form bundles of parallel wires extending through a plurality of selectors. The present invention has for its object to provide for a uniform distribution 30 of the connections also in systems of this kind. For this purpose the group selectors are provided with a number of movable switching members corresponding to the different groups of lines and adapted to be set in known manner to select a particular line in 35 the appertaining group the switching members belonging to different selectors but operating in the same group of lines being adapted to select the different lines of this group in a different order of sequence or from different 40 initial positions respectively.

The invention will be more closely described with reference to the accompanying drawings, in which Figures 1 to 3 show the invention as applied to selectors of the kind in which 45 the incoming and outgoing lines extend through the contact field in different directions perpendicular to each other and are connected at the points of intersection to contacts which can be selected and operated by 50 means of a selector mechanism provided in

front of the contact field. The characteristic feature of such selectors is that they have no displaceable contact arms. The invention is, however, not limited to such selectors as it may be applied with advantage also to 55 selectors having displaceable contact arms. Figure 1 is a section on the line 1—1 of Figure 2. Figure 2 is a front view of a number of group-selectors and the appertaining contact field. Figure 3 is a horizontal 60 section on the line 3—3 in Figure 1. Figures 4 to 9 are side views and plan views of different modifications of the switching member. Figures 10 and 11 are a side view and a 65 plan view respectively of a group-selector having contact arms and provided with an auxiliary selector for the selection of the contact arms.

In the construction shown in Figures 1 to 3 the wires of the contact field as well as the 70 selector mechanisms are mounted in a frame work consisting of a number of vertical beams 1 which are joined together at their upper and lower end by means of horizontal bars 2, 3. Between the two beams of each pair 75 there is provided a number of for instance ten or fifteen identical selector mechanisms with appertaining contact fields. The latter consist in the example shown of ten parallellepedical bundles of horizontal wires 4, 80 preferably bare wires, disposed above one another, and a number of bundles of wires 5, corresponding to the different selector mechanisms and extending vertically. The wires 4 may for instance constitute the outgoing 85 lines, whereas the incoming lines are represented by the vertical wires 5. The wire field is carried by a frame work arranged between the horizontal bars and consisting of two vertical bars 6, 7 and a number of horizontal bars 8 of an angular cross-section 90 which are screwed to the bars 6, 7, and further a number of vertical bars 9 which are screwed to the horizontal bars 2, 3. The wires 4 are drawn through holes in insulating 95 plates 10 which are screwed to the bars 9. Each plate 10 carries a bundle of wires comprising ten lines each consisting of three wires, viz the two speaking line branches and a test wire. The three wires of each line form 100

a horizontal layer of wires. The vertical wires 5 are similarly drawn through holes in insulating plates 11 screwed to the horizontal bars 8. Each selector mechanism has one incoming line consisting of three wires 5.

The connections between the incoming and outgoing lines are established by means of contact arms 12 arranged at the points of intersection of the different lines and which 10 consists of elastic metal strips, which are soldered or otherwise connected to the wires 5. They are arranged so as to extend horizontally between the horizontal layers of wires 4, so that the ends of the contact arms will be 15 located right above the corresponding wires 4. Each set of three contact arms is arranged to be operated from the selector mechanism through the medium of a thin plate 13 of insulating material placed on the contact arms 20 and adapted to be retained in position by the wires 5 passing through holes in the plate. Said plate is normally kept in a raised horizontal position by the contact arms 12. Inserted in the front edge of said plate there 25 is a piece of metal 14 serving as an actuating point for the selector mechanism as will be described hereinafter.

The selector mechanism comprises a number of switching members 15. In the example 20 shown there are ten such members, which consist of sleeves thrust on a vertical shaft 16 and provided with contact actuating members consisting of radial pins 17 arranged along a helical line. By rotating the sleeve said pins 35 can be brought successively in operating position to actuate the metal pieces 14 on the plates 13, so that the different groups of contact springs 12 are successively brought in contact with the appertaining wires 4. The 40 sleeves 15 are mounted in journals 18 secured to the left hand side of a plate 19, which forms the frame in which the selector mechanism is mounted. In the example shown each selector mechanism is assumed to establish 45 connection between one incoming line and one hundred outgoing lines, the latter being arranged in ten groups each containing ten lines. Thus, each line group has allotted to it a separate switching sleeve 15. In order to 50 be able to establish connection in any line group wanted, the switching sleeves 15 are arranged to be coupled mechanically in and out of connection with the shaft 16 by a vertical movement of the latter. The coupling 55 is effected by means of pins 20 provided on the shaft, said pins being adapted, upon the shaft being raised, to enter notches 21 in rings 22 which are fastened inside the sleeves to their upper ends. The selecting of the different switching sleeves is effected by means 60 of a step-wise vertical movement of the shaft 16 from its normal position. By raising the shaft one step the first i. e. the lowermost sleeve 15 is coupled to the shaft 16 by the 65 lowermost pin 20 entering the notch 21 in

said sleeve. If connection is wanted with a line in the first group, the shaft 16 is then rotated stepwise the sleeve 15 being carried round by the pin 20. The lowermost pin 17 on said sleeve will then press against the metal 70

piece 14 of the lowermost plate 13, which therefore will press the appertaining group of contact arms 12 into contact with the corresponding wires 4. Figures 1 and 3 show the position of the mechanism after the sleeve 75 15 has thus been rotated for one step in the direction of the arrow shown in Figure 3. If the shaft 16 is rotated for another step, the first group of contact arms is released and is caused by the elasticity of the contact arms to 80 resume its normal position, the second group of contact arms being instead actuated by the second pin 17 on the sleeve 15. In this way evidently any wanted group of contact arms may be selected and operated. During 85 the switching operation in one line group the switching sleeves 15 of all the other line groups are inoperative, as the appertaining coupling pins 20 are not then in engagement with the corresponding sleeves. If the shaft 90 16 is at first raised two steps, the second switching sleeve 15 will be coupled to the shaft 16 by the appertaining pin 20 entering into engagement with the notch 21 of the second sleeve. The coupling pin 20 of the first 95 switching sleeve will then be located above this sleeve and the following rotation of the shaft 16 will therefore only cause the second switching sleeve to be rotated. Similarly the third, fourth etc. switching sleeves can be 100 coupled to the shaft 16 by lifting the shaft three, four etc. steps. After the end of the conversation the shaft 16 and the sleeve 15 are restored to normal position by a further 105 rotation of the shaft 16 in the same direction, until it reaches its normal position, in which the pins 20 are all right below the notches 21 of the appertaining sleeves.

The motion mechanism consists of a lifting electro-magnet 23 and a rotary magnet 110 24 with appertaining driving pawls 25 and 26 respectively operating on teeth 27 and 28 respectively on the lower end of the shaft 16. During the operation of the electro-magnet 23 the shaft is maintained in a raised 115 position of the pawl 29, which together with the pawl 25 may be brought out of engagement with the teeth 27 by means of a restoring electro-magnet 30. The magnets 23, 24 and 30 are mounted together with the shaft 120 16 and the appertaining switching sleeves 15 on the left hand side of the appertaining frame 19, which thus carries the whole selector mechanism. The frame 19 is secured to the transversal bars 2, 3 by means of 125 screws 31, 32 in such a manner that it can be easily detached by loosening said screws. The mounting of the frame in its position is facilitated by its lowermost edge being 130 guided in a slot 33 provided in a base plate

34 screwed to the lower bar 3. A transversal bar 35 serves as a support for the frame while being inserted in its place.

The setting movements of the selectors 5 may also be continuous in which case the shaft 16 is arranged to be driven from rotating shafts or the like according to methods well known in the automatic telephony.

In a selector of the kind above described 10 the present invention may be applied in different ways. For instance, the switching members 15 belonging to different selectors but operating in the same line group may be displaced relatively to each other so that, 15 while being rotated, they will select and operate the different sets of contacts in a different order of sequence. The arrangement may for instance be such that one selector, when started to select an idle line, may first 20 operate the lowermost set of contacts and then the other sets of contacts in succession in the manner above described, whereas the other selectors may first operate the second, the third etc. set of contacts and then the remaining 25 sets of contacts in succession. A similar result may be obtained by providing the different selectors with different switching sleeves for instance of the kind shown in Figures 4 to 9, which differ from the switching sleeves shown in Figures 1 to 3 by the arrangement of the contact operating pins 37. In a group of three selectors for instance the first selector may have a switching sleeve of the kind shown in Figures 4 and 5, the 30 second selector a switching sleeve according to Figures 6 and 7 and the third selector a switching sleeve according to Figures 8 and 9. In Figures 4 and 5 the arrangement of the pins 17 is such that, when rotating the sleeve from its initial position in the direction of the arrow in Figure 5, the different sets of contacts are operated in succession from above and downwards. In the arrangement of the pins 17 according to Figures 6 35 and 7 the different sets of contacts will be operated in succession from below and upwards. In the arrangement according to Figures 8 and 9, on the other hand, the sixth set of contacts will be first operated and then 40 in succession the 7th, 8th, 9th, 10th, 5th, 4th, 3rd, 2nd and 1st sets of contacts. By varying the arrangement of the pins 17 on the switching sleeves at the different selectors in this way the traffic may be distributed 45 over the junction lines of a group.

In the arrangement above described it has been assumed that the switching sleeves have a fixed normal position to which they are restored after the end of the conversation. 60 The arrangement may, however, easily be modified so that the restoring of the switching sleeves may be dispensed with. For this purpose the rings 22 inserted in the ends of the switching sleeves may be provided with 65 ten notches 21 corresponding to the ten dif-

ferent setting positions of the sleeve. It is evident that in such an arrangement the switching sleeve may be left standing in any setting position even after the end of the conversation if instead thereof the telephone 70 connection is broken at another point of the connection. It will therefore only be necessary to restore the shaft 16 in a vertical direction and the pins 20 will then pass freely through the notches 21 in the rings 22. When 75 the selector is taken into engagement the next time, the shaft 16 is first raised in the same manner as before so as to be coupled with the switching sleeve wanted. The latter may then be in any angular position. 80 Thereupon the rotation of the switching sleeves will take place in the manner above described. In this arrangement the different switching sleeves 15 of the different selectors 85 may be identical in respect of the arrangement of the pins 17 as the desired distribution of the traffic will be attained by the different switching sleeves being started from different initial positions.

Figures 10 and 11 illustrate a group-selector having movable contact arms and the contact field of which consists of bare wires 36 extending perpendicularly to the shafts 37 of the selectors and forming a single vertical layer of wires. Secured to the selector shaft 37 are a number of cylindrical sleeves 38 of insulating material carrying contact pins 39 arranged helically on the sleeve. By rotating the shaft said contact pins may be brought successively in contact with the line wires 36, 90 whereby any wanted line may be selected similarly as above described. The contact pins 39 are electrically connected together and connected to contact rings 40, 41, 42 at one end of the sleeve, wipers 43, 44, 45 being provided for connecting said rings with the corresponding wires of a junction line 46. If the shaft 34 is provided with ten such sleeves, there will be ten junction lines which are connected to the fixed contacts of an auxiliary 95 selector 47 by means of which any junction line may be selected in any wanted group of outgoing lines 46. This selector need not have any fixed normal position. After the end of the conversation it may thus be left 100 standing in the position in which it has been previously set. When taken into engagement the wanted group is first selected by means of the auxiliary selector 47 and then a disengaged line in this group is searched for by 105 rotating the shaft 37 for instance by means of an electro-magnet 48, a driving pawl 49 and the ratchet wheel 50 on the shaft 37. During the rotation all sleeves 38 partake in the rotary movement of the shaft but only 110 one of them is electrically operative.

I claim:

1. In an automatic telephone system the combination of a plurality of group selectors, 115 a plurality of numerical groups of outgoing 120 lines, a plurality of selector sleeves, each 125 selector sleeve having a plurality of pins 130

lines accessible in common to said group-selectors, incoming lines of said group-selectors connected to fixed sets of contacts of the contact fields of the group-selectors, a plurality 5 of switching members in each group-selector corresponding to the different groups of lines and each provided with a plurality of contact operating members for mechanically actuating the sets of contacts of the appertain-
10 ing group in succession, the switching members of different group-selectors pertaining to the same numerical group being arranged to actuate the sets of contacts in a different order of sequence while being started each
15 time from a predetermined position.

2. A group selector as set forth in claim 1 in which the switching members belonging to the same line group have predetermined normal positions to which they are 20 restored after disconnection of the telephone connection.

3. A group selector as set forth in claim 1 in which the switch members are rotatably arranged and driven on a common shaft in 25 the same direction.

In testimony whereof I affix my signature.

DAVID LAURENTIUS LIENZÉN.
